[57] CLAIM

The ornamental design for a spray nozzle for attachment to a pressurized spray can, as shown and described.

DESCRIPTION

FIG. 1 is a perspective view showing my new design with the nozzle in a first position;

FIG. 2 is a perspective view with the nozzle in a second moved position wherein it has been pivoted 90 degrees from the first position;

FIG. 3 is a front view of the position in FIG. 2;

FIG. 4 is a back view of the position in FIG. 2;

FIG. 5 is a top plan view of the position in FIG. 2;

FIG. 6 is a bottom view of the position in FIG. 2;

FIG. 7 is a right side view of the position in FIG. 2; and,

FIG. 8 is a left side view of the position in FIG. 2.
